UNITED STATES PATENT OFFICE

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

SHOE MACHINE

Original application filed June 16, 1920, Serial No. 389,397. Patent No. 1,631,155, dated June 7, 1927.
Divided and this application filed October 23, 1926. Serial No. 143,972.

The present invention relates to shoe machines, it more particularly concerning apparatus for the attachment of heels to shoe-bottoms.

It has for its object the provision of a machine organized for the insertion of nails of the type disclosed in my application Serial No. 143,971, filed on the same date as the present application. Such nails are usefully employed for the attachment of Louis and like heels, which, from a tread of small diameter and a still smaller neck rising from the tread, expand by a sharp curvature to a much greater diameter at the heel-seat. To 10 drive the attaching nails straight through such a heel vertically to the tread-surface, causes their clinching in the shoe-bottom to be so widely separated from the edge of the heel-seat-end as to produce little resistance 15 to gaping at the rand-crease. If the nails are driven in an inclined direction, only a small divergence can be given to entering extremities if their bodies are to remain within the walls of the contracted portion of the 20 heel. By the employment of this invention, 25 suitably formed nails may be kept safely within the neck of the heel, and yet the points caused to enter the shoe-bottom in such close proximity to the edge of the expanded portion that a good joint is assured. 30

A feature of the invention may be found in a machine including a nail-receiving device or devices having, in a novel relation, a passage and means, as a slot, opening from and extending longitudinally of the passage and arranged to prevent rotation of a nail therein. This slot, when a nail, such as that of the previously mentioned application, is traveling through the passage in the direction of its axis, will receive its guide-projection to hold it in the desired relation to the outside of the heel, it being at a definite angle with respect to the work-support, by which the shoe being operated upon is presented to the nailing mechanism. Such an arrangement, to maintain the nails in predetermined angular positions about their longitudinal axes, is shown as applied to both the loading device and the die-block of the machine. 40

To facilitate the positioning of a nail with

respect to the guide means, as to bring its projection into co-operation with the directing slot of a receiving device, as another feature of the invention, said receiving device is provided with means arranged to turn the nail about its longitudinal axis. In the present embodiment of the improved machine, this is accomplished by an inclined surface situated in proximity to the upper extremity of a nail-receiving passage, where the nail-projection strikes the surface and turns the nail until said projection is in position to enter the guide-slot. 55

In the accompanying drawings,

Fig. 1 shows in side elevation a portion of a shoe which has been heeled by the machine of my invention; 55

Fig. 2 is a plan view of the bottom of the body of a heel before the application of the top-lift; 70

Fig. 3 illustrates the heel-body partially pricked or perforated in preparation for driving the nails;

Fig. 4 is a broken perspective view of a nail for use in the illustrated form of my improved machine; 75

Fig. 5 is a partial front elevation of such machine;

Fig. 6 is an enlarged sectional detail taken through the loading device and die-block of the machine, with a shoe to be heeled in co-operation with the die-block upon its jack; 80 and

Fig. 7 is a top plan view of the nail-receiving cylinder mounted upon the loading device. 85

At S in Fig. 1 appears the bottom counter-portion of a shoe having attached to it a heel H of the Louis type, the body of which has a neck-portion 10 of relatively small diameter, expanding slightly to the tread-end 12 and heavily in the opposite direction to the heel-seat-end 14, the rear and sides of the heel thus being upon ogee curves. The transverse dimension of the neck 10 may be as little as five-eighths of an inch, while at the heel-seat the diameter may be nearly three times this. Were the attaching nails N driven straight through the heel into the shoe-bottom in a direction at right angles to the 100

tread-surface, they would come within an area approximately of a ten cent piece, and would obviously be ineffective to hold the heel closely to the upper at the rand-crease. If the nails were driven along straight lines in an inclined direction to enter the shoe-bottom at the points illustrated in Fig. 1, they would, as is indicated at α , lie almost at the surface of the neck, where they might be struck by the trimming knife, injuring this and spoiling the heels. To keep the nails fully within the substance of the neck-portion and at the same time bring them into the shoe-bottom well toward the periphery of the heel-seat, I employ the heel-attaching machine, a particular embodiment of which is illustrated, in part, at L in Fig. 5. This has a frame 16 carrying a die-block 18, with which co-operates a jack or work-support 20, reciprocatory drivers 22 and an oscillatory loading device or devices 24, each loading device including a loader-block 26. Instead of containing the usual nail-receiving passages, the die-block and loader-block, since the nails used with the type of heels now under consideration are long, are each bored to receive vertical, cylindrical holders 28 and 30, respectively, extending above the blocks and held in place by set-screws 32. Both holders are fixed as to their angular position about their longitudinal axes by keys 34, which are seated in recesses in the blocks. Through the holders are vertical nail-receiving passages 36 grouped according to the points at which the nails are to enter the heel H, pressed against the under side of the die-block and against the bottom of the shoe S which is jacked upon the work-support 20. When the loader-cylinder 30 is in its nail-delivering position over the die-cylinder 28, the two sets of passages 36 are in vertical alinement, so that the nails in the former, released by the usual shutter mechanism, will fall directly into the passages of the latter, there resting with their points upon the heel. Extending longitudinally of each of the nail-receiving passages in both holders and opening therefrom are slots 38 of less width than the passages and adapted to admit lateral guide-projections 40 from the heel-attaching nails N arranged with their axes longitudinally of the passages. Each of these projections is in the form of a small fin struck out of the body of a nail and extending longitudinally at one side in proximity to but somewhat removed from the end opposite the heel-entering point. This point 42 is preferably formed by a surface 44 inclined, as by cutting or bending, from one side of the body to the other and bearing a definite angular relation about the longitudinal axis of said body to the projection 40, it being here shown as diametrically opposite to it. When the nails are inserted in the loader-passages, the combined relation between the slots 38, projections 40 and the

heel H positioned upon the jacked shoe, presents the nail-points to the tread-surface of the heel-body with the inclined surfaces turned inwardly from the corresponding elements of the outer curved surface of the heel, opposite which the nails are to be driven. The angular positions of all these parts are clearly shown in Figs. 2 and 7. Since, when the nails are dropped, into the passages in the loader-cylinder 30, but a relatively small portion have their projections fortuitously alined with the slots 38, I prefer to provide means for turning the other nails about their longitudinal axes, so that the projections will be caused automatically to enter the slots. As herein illustrated, this means consists of inclined surfaces 46 situated between the slots at their upper extremities, these surfaces being furnished by a frusto-conical end of the cylinder 30. After the point of a nail has been introduced into one of the passages 36 of the cylinder 30 and dropped, its weight, when the projection 40 strikes a surface 46, causes the nail to rotate about its axis until the projection enters the slot, allowing said nail to proceed properly along the passage to the alined passage in the die-cylinder 28.

In attaching a shoe-heel in accordance with this invention, since, to obtain the best results, the paths to be first followed by the nails should be substantially vertical to the tread-surface of the heel H which is to be attached to the shoe S, this heel is first perforated, as indicated at 48 in Fig. 3 of the drawings, as by a pricking machine, to a depth at which the inner ends of the perforations are at or near the transverse plane of the heel at which the neck-portion begins to expand toward the heel-seat-end. This having been accomplished, the heel is associated with the jacked shoe in the attaching machine L, and forced in the customary manner against the die-block beneath the nail-passages in the die-cylinder 28. A load of nails N is dropped into the loader-cylinder 30, their projections 40 either directly entering the slots 38 or being turned into co-operation therewith by their contact with the surfaces 46. This load is transferred to the die-block, by which the nails are presented to the heel, and the loader being swung back to its initial position, the drivers 22 descend and force the nails into the heel. At first, as they pass through the pricked perforations, their paths are straight, as determined by such perforations, but when the points 42 penetrate the material of the heel at the ends of the perforations, the resistance opposing their advance exerts a component of force acting at right angles to the axes of the nails. This causes their gradual divergence from straight lines in directions opposite to the inclines 44, or toward the outside of the heel, these portions of the paths being curvilinear, as appears in Figs. 1 and 6 of the drawings. Such paths,

- being maintained in the proper relation to the outside of the heel by the perforations and by the relation between the guide-slots 38 and the nail-surfaces 44, cause the nails at 5 all points between the tread-end and the heel-seat-end to be sufficiently removed from the sides, so there is no danger of their breaking through or being struck by the trimming knife, and still the nails are brought to such 10 clinching points 50 in the shoe-bottom that they are relatively close to the rand-crease, holding this against gaping. The curvature of the nail-paths beyond the extremities of the perforations 48 will depend upon the 15 character of the resistance offered to them and upon the inclination of the surfaces 44. The last factor is a controllable one, the degree of divergence from a straight path varying inversely as the inclination of the point. 20 That is, the sharper the point or the more acute its angle with respect to the longitudinal axis of the nail, the less will be the departure of the nail from the vertical. Consequently, by properly forming the points of 25 the nails, they may be caused to closely follow the sides of heels of different contour and to emerge into the desired proximity to the rand-crease. The action of the drivers 22 continues until the projection 40 strikes and 30 bears with some pressure against the tread-end of the heel-body, it performing, in addition to its angular positioning function, that of the flange upon the well-known collar-nail, holding the heel-lifts against separation. 35 Upon the extremities 52 of nails which project beyond the tread-end, a top-lift T is then spanked by the heel-attaching machine in the usual manner, thus completing the heel-ing operation. 40 The method of attaching heels by the herein described machine and a shoe thus heeled are made the subject of application Serial No. 389,397, filed June 16, 1920, of which the present case is a division. This application 45 became United States Patent No. 1,631,155 on June 7, 1927.
- Having described my invention, what I claim as new and desire to secure by Letters Patent of the United States is:
- 50 1. In a heel-attaching machine, nail-receiving devices each having a nail-passage, the devices being relatively movable to aline the passages, and guide means constructed and arranged to co-operate with a surface upon a 55 nail and thereby prevent the rotation of said nail in the passages.
2. In a heel-attaching machine, a device having a passage arranged to receive nails with their axes lying longitudinally of said 60 passage and a slot opening from and extending longitudinally of the passage, said slot being arranged to guide nails in their travel through said passage.
3. In a heel-attaching machine, a work-support, and a nail-receiving device having a 65 nail-passage and a slot opening from and extending longitudinally of the passage, the slot having a definite angular relation to the work-support and being arranged to guide nails in their travel through said passage. 70
4. In a heel-attaching machine, a loading device having a passage arranged to maintain a nail in a definite angular relation about its longitudinal axis, a die-block provided with a passage similarly arranged and with which the passage in the loading device may be alined, and driving means co-operating with the die-block. 75
5. In a heel-attaching machine, a work-support, a loading device having a passage arranged to maintain a nail with respect to the work-support in a definite angular position about its longitudinal axis, a die-block with which the work-support co-operates provided with a passage similarly arranged to that of the loading device and with which the passage in said loading device may be alined, and driving means co-operating with the die-block. 80
6. In a heel-attaching machine, a nail-receiving device provided with a passage and means situated at the entrance to the passage and arranged to turn a nail about its longitudinal axis. 85
7. In a heel-attaching machine, a nail-receiving device provided with an inclined surface arranged to co-operate with a nail to turn it about its longitudinal axis. 90
8. In a heel-attaching machine, a nail-receiving device having a nail-passage, guide means constructed and arranged to co-operate with a surface on a nail and thereby prevent rotation of said nail in the passage and means associated with an extremity of the passage for positioning the nail with respect to the guide means. 95
9. In a heel-attaching machine, a nail-receiving device provided with a substantially vertical passage, a slot opening from and extending longitudinally of the passage and inclined nail-engaging surfaces at the upper extremity of the passage and at opposite sides of the slot. 100
10. In a heel-attaching machine, nail-receiving devices each having a nail-passage, the devices being relatively movable to aline the passages, and guide means extending longitudinally of each passage, said guide means being arranged to co-operate with a projection upon a nail and registering when the passages are alined. 105
11. In a heel-attaching machine, nail-receiving devices each having a nail-passage, the devices being relatively movable to aline the passages, there being a guide-slot opening from each passage and being of less width than said passage. 110
12. In a heel-attaching machine, a nail-receiving device having a nail-passage, guide means constructed and arranged to co-operate with a surface on a nail and thereby prevent rotation of said nail in the passage. 115
13. In a heel-attaching machine, a work-support, and a nail-receiving device having a nail-passage and a slot opening from and extending longitudinally of the passage, the slot having a definite angular relation to the work-support and being arranged to guide nails in their travel through said passage. 120
14. In a heel-attaching machine, a work-support, and a nail-receiving device having a nail-passage and a slot opening from and extending longitudinally of the passage, the slot having a definite angular relation to the work-support and being arranged to guide nails in their travel through said passage. 125
15. In a heel-attaching machine, a work-support, and a nail-receiving device having a nail-passage and a slot opening from and extending longitudinally of the passage, the slot having a definite angular relation to the work-support and being arranged to guide nails in their travel through said passage. 130

ate with a surface on a nail and thereby prevent rotation of said nail in the passage, and nail-positioning means co-operating with the passage.

5 13. In a heel-attaching machine, a nail receiving device having a passage through which nails travel in the direction of their axes and with a guide-slot opening from the side of said passage and means associated with the passage and constructed and arranged to rotate a nail about its axis and thereby position it with respect to the guide-slot.

6 In testimony whereof I have signed my
name to this specification.
